Filed May 21, 1959, Ser. No. 56,014

Term of patent 3½ years

(Cl. D14—3)

Fig 1

FIG. 1 is a side elevational view of a trailer for animals or the like, embodying my new design;

FIG. 2 is a front side perspective view; and

FIG. 3 is a back side perspective view.

The side not shown is essentially the same in appearance as the side shown except in the omission of the larger door.

I claim:

The ornamental design for a trailer for animals or the like, as shown and described.
